ELECTRORADIOGRAPHY

Roland M. Schaffert, Robert C. McMaster and William E. Bixby, Columbus, Ohio, assignors, by mesne assignments, to The Battelle Development Corporation, Columbus, Ohio, a corporation of Delaware

Application February 2, 1950, Serial No. 142,024

3 Claims. (Cl. 250—65)

1

This invention relates to electroradiography, an electrical method for preparing radiographic images produced by penetrating radiation.

It is an object of this invention to provide an electrical method for producing radiographs which is rapid and provides for the completion of a radiographic print within a few seconds after completion of the exposure.

It is another object of this invention to provide an economically advantageous method for producing radiographs.

Other objects and advantages of this invention will become apparent in view of the following disclosure thereof especially when considered in the light of the attached drawings wherein,

Figure 1 shows one way of sensitizing a plate preparatory to obtaining a radiographic image,

Figure 2 illustrates one particular way of making the X-ray exposure,

Figure 3 shows two ways of developing the radiographic image on the plate, and

Figure 4 shows a cross-section through a specimen used in determining the contrast sensitivity of the process together with a drawing representative of the electroradiograph obtained in such test.

Referring now more particularly to each of the drawings, it will be seen that in Figure 1 a sensitive plate 11 is being electrostatically charged by corona discharge from a sensitizing wire 12. Such sensitizing or discharge wire 12 is shown supported by an insulating frame 13 fixed to a supporting table or bench 15. Also illustrated schematically is a high-voltage source 16 for energizing the corona discharge wire 12.

In Figure 2 is shown, for illustrative purposes, a particular arrangement which may be used for exposing the sensitive plate to the X-ray radiations. In this particular set-up the sensitive plate 11 is shown in place in a plate-holder 21 which should be of such material as not to absorb the X-rays. Plate 22 is a lead plate for shielding purposes. A source 24 of X-rays is shown schematically while the remainder of the drawing is in section. An article 25 being examined is represented here as a metal sandwich made up of successive layers of metal as will be more fully described in connection with Figure 4. It will be understood, of course, that this article might be any object which it is desired to X-ray.

Figure 3 illustrates two of the ways in which the electrostatic image produced on plate 11 by an exposure process such as illustrated in Fig-

2

ure 2 may be developed. In the examples shown the plate 11 is placed in a tray 30. Stops 31—31 are positioned in the bottom of the tray to hold plate 11 in place during the process. A suitable developer 33 is flowed back and forth across the plate 11 by tipping tray 30 first one way and then the other. As will be pointed out later the developer particles 33 adhere to those areas of plate 11 which have an electrical charge residing thereon. In (b) it is illustrated how plate 11 may be placed with its sensitive face down over a chamber in a container 35 wherein an atmosphere saturated with developer particles is maintained. An agitator 37, or similar device, may be provided for the purpose of circulating and stirring up the developer particles. Agitator 37 may be driven by a suitable motor, not shown. Here again developer particles striking charged areas will adhere thus making visible the image produced by the exposure step.

Figure 4 shows a specimen used in tests to determine contrast sensitivity for the process. The specimen consisted of a metal sandwich made up of three layers of metal (aluminum was used) 40, 41, and 42. In the middle layer 41 were circular holes of varying diameters as indicated at 43, 44, 45, 46, 47, and 48. In part (b) of the figure is a pictorial representation of the electroradiograph obtained when using such specimen and illustrating how the regions of lesser thickness are indicated by white, or lighter colored areas, on the electroradiograph.

In general, this invention relates to a dry, electrical method for producing images created by penetrating radiations.

An important factor in the present method is the sensitive plate which is used in carrying out the various steps of the invention. This plate consists of a conductive backing plate upon which a layer of semi-conductive material is coated. The manner of preparation of such plates forms no part of the present invention and will not be described here except to mention some materials which are satisfactory as coating materials. These include selenium, sulphur, anthracene, mixtures of sulphur and anthracene, mixtures of selenium and sulphur and other materials sensitive to penetrating radiations.

The first step in the process of the present invention is to provide an electrostatic charge on the surface of the sensitive plate. This is preferably accomplished by subjecting the plate to a corona discharge from thin wires or needles as illustrated in Figure 1. Other methods are

also suitable, such, for example, as frictional methods.

Once an electrostatic charge has been produced upon the sensitive plate the essential step of the present process is carried out. This step comprises exposing the object to be radiographed to penetrating radiations while the object is interposed between the uniformly charged sensitive surface and the source of the radiated energy. It will be understood that the term "penetrating radiation" as herein employed relates to X-rays, gamma rays, Grenz rays and any other penetrating electromagnetic wave radiation capable of exciting suitable semi-conductors to a state of increased conductivity. The term may be further defined as radiation capable of penetrating a layer of matter, no matter how thin, which is opaque to ordinary visible light. The object to be radiographed may be suspended in any desired manner above the sensitive surface, or otherwise positioned between the radiation source and the sensitive surface during the exposure step. Arrangements may also be provided wherein the radiations pass through a hole in the plate, strike the test object and are reflected back to the plate. According to well-known techniques provision may be made for either the object and/or the radiation source to move so as to provide clear images, to provide two or more stereoscopic views, to permit radiographing the object from two or three mutually perpendicular directions, or to permit other desired views. Arrangements wherein the sensitive plate is placed within a hollow object, with the source on the outside, or vice versa, are also possible. In case an extremely sensitive material is used, it may be necessary to perform the exposure step in the dark, since many charged semiconductive materials are readily discharged by light. For example, a charged selenium-coated plate should be exposed to the penetrating radiations in darkness, while a charged anthracene-coated plate may be so exposed in the light.

The step of exposing the charged, sensitive surface to penetrating radiation through the object being tested, or radiographed, will produce a condition on the sensitive surface wherein those areas which have been subjected to high intensities of the radiations will become discharged, while other areas will be only partially discharged, in accordance with the amount of penetrating radiation which has struck there. Since the amount of energy reaching the plate will depend upon the amount absorbed by the object being radiographed, and since the amount so absorbed will be related to the thickness of the object at various points, to the composition of the object, etc., it will be apparent that a charge pattern will be formed on the sensitive surface wherein the charge pattern conforms to a positive image of the object being radiographed. The next step in the process of the present invention is to develop this charge image and make it visible.

The development step in this process is preferably done by contacting the charge image with a suitable powder or other dry developer. This may be accomplished, for example, by flowing the developer powder back and forth across the charged surface. It will be found that the developer particles adhere to the charged areas on the plate. Various resinous powders have been found satisfactory for this developing process, and it has also been found that a mixture of de-

veloper powder with a granular carrier material produces a good combination for developing the radiographic images. Figure 3 illustrates two ways by which development may be achieved.

5 The visible image formed by the developing or dusting process may be inspected at once. However, a permanent copy of the image may be obtained in a few seconds and it is often desirable to obtain such a copy in addition to inspecting the original image visually. The obtaining of a copy may be accomplished in numerous ways. For example, an adhesive coated sheet may be pressed against the powder image bearing plate and transfer of the powder particles thus effected. Chemical transfer methods involving solvents, etc., are also convenient. A preferred method, however, comprises contacting the image bearing plate with a sheet or material to which the image is to be transferred 10 and subjecting such assembly to a corona type discharge which will spray electrostatic charges onto the transfer material. By electrostatic action the powder image is transferred to the second material. This may be accomplished by the identical device shown in Figure 1. The transferred image may be rendered permanent by fusing or by chemically fixing to the transfer material.

15 It will be understood also that electrostatic scanning methods may be adapted to reproduce the electrostatic image pattern created during the exposure step. This may be accomplished by passing a scanning head over the sensitive surface bearing the charge pattern, whereupon the image may be reproduced on a screen in response to the signals from the scanning head.

20 It will be apparent that a new, rapid and useful method for obtaining radiographs has been set forth in the description above. A further consideration of the requirements and properties of radiographic methods and images will serve to further demonstrate the advantages and desirabilities of the present method.

25 An important property of all radiographs relates to their definition or resolving power, 45 which can best be described in terms of the number of lines per inch of a high-contrast specimen which can be clearly shown by the X-ray image. In this respect, experimental images 50 have been obtained of a U. S. Standard #30 sieve, wherein each of the 0.0130-inch diameter wires, spaced 0.0232-inch apart, are clearly revealed. Similar images of U. S. Standard #120 sieve show clearly wires of 0.0034-inch diameter, spaced 0.0049-inch apart; while excellent images 55 of 200-mesh sieves establish the definition of the present electroradiographic method as at least 200 lines per inch, which value is not intended to be limiting, but merely illustrative. This observed definition compares very favorably with 60 the 80 lines per inch obtained under optimum conditions with a fine-grain industrial fluoroscopic screen under laboratory observation conditions. These electroradiographs were obtained 65 using a 20 second exposure to an industrial X-ray unit at 150 kilovolts peak and 10 milliamperes.

70 Another basic factor in the evaluation of X-ray technique in radiography is the per cent contrast sensitivity of the process. This is expressed in terms of the per cent change of the total material thickness that is just detectable in the interpretation of the radiographs. Two per cent contrast sensitivity is common in industrial radiographic work and one per cent may be obtained under most conditions. In fluoroscopy, however, the

typical contrast sensitivity is of the order of 15 per cent. Even under optimum conditions industrial fluoroscopic images have seldom, if ever, shown contrast sensitivities better than six or seven per cent. A preliminary estimate of the 5 large area contrast sensitivity of electroradiography has been obtained by using the process to produce electroradiographs of sandwiches made up to thick sheets of aluminum containing an internal aluminum layer of nominal thickness with several drilled holes. For example, images have been obtained with a metal sandwich $\frac{3}{4}$ -inch thick having a series of holes of different diameters in the middle $\frac{1}{4}$ -inch section. These are 10 revealed clearly in the electroradiograph (see Figure 4). Similar holes present in a $\frac{1}{16}$ -inch thick layer of aluminum sandwiched between two $\frac{1}{2}$ -inch layers of aluminum sheet containing no holes were equally detectable. This latter test corresponds to about six per cent contrast sensitivity and is only representative of the degree of contrast possible according to the present method, since optimum conditions have not yet 15 been thoroughly investigated. These images were produced by a 60 second exposure to an industrial X-ray unit at 150 kilowatts peak and 10 milliamperes.

It has been found that electroradiography possesses a wide latitude range while retaining a good local contrast sensitivity. Latitude may be 20 defined as the ability to obtain a usable image with widely varying exposure, or with widely varying thicknesses of material in a single exposure. Successful electroradiographs of objects shown in Figure 1 have been made using X-ray 25 voltages from 60 to 200 kilovolts peak.

Electroradiographic studies show increasing contrast with increasing exposure time, at least up to a definite optimum time. A decrease in background density accompanies this effect. It 30 is of interest that electroradiography produces direct positive images, whereas standard radiography on X-ray film gives negative images.

In connection with the present invention, it 35 will be recognized, of course, that it is not required that an entire object be radiographed, but that ready provision may be made for radiographing any desired portion of any object and the word "object" in the claims should be so interpreted.

An alternative manner of practicing this invention arises when the sensitive surface layer material is sensitive to light as well as to penetrating radiations. As has already been noted, 40 selenium is an example of such material. When a material having these characteristics is used it brings about the possibility combining light, or non-penetrating radiations, with any of the penetrating radiations in carrying out the exposure step. Exposure to the non-penetrating radiations and to the penetrating radiations may be 45 made either simultaneously or separately.

The advantages and desirable features of the present method will be readily apparent to those skilled in the art in view of the above description. 50 Numerous variations and equivalent procedures in carrying out the various steps have been pointed out and others will be apparent to persons skilled in the art, as will other advantages and properties not herein specifically pointed out.

For example, plates used in this process may be used repeatedly in the electroradiographic procedure. This requires only that any powder particles adhering to the plate be removed prior to 5 repeating the steps of the process. Such cleaning may be readily effected by passing a granular material back and forth across the plate several times to pick up any adhering powder particles. Other cleaning procedures are also possible, of course.

It will be further apparent that the method of this invention may be used for other purposes than the production of electroradiographs of articles. For example, X-ray diffraction patterns, records of X-ray and other fields, or other patterns produced by the radiation source may be provided. The device may be used as a simple radiation detector or integrator.

In view of the above disclosure and description 20 the present invention will now be more specifically described and its scope defined by the attached claims.

What is claimed is:

1. The method of electroradiography comprising the steps of charging the surface of a plate having a semiconductive selenium coating, exposing the charged plate to X-ray radiation while an object to be tested is positioned between the X-ray source and the charged selenium plate, dusting the surface of such exposed plate with a resinous material, transferring the image thus produced to a second surface, and fixing such transferred image to said second surface.

2. The method of electroradiography comprising the steps of charging the surface of a plate having a semiconductive selenium coating, exposing the charged plate to X-ray radiation while an object to be tested is positioned between the X-ray source and the charged selenium surface, dusting the surface of such exposed plate with a dry developer material, transferring the image thus produced to a second surface, and fixing such transferred image to said second surface.

3. The method of xeroradiography comprising the steps of charging the surface of a plate having a semiconductive selenium coating, exposing the charged plate to X-ray radiation while an object to be tested is positioned between the X-ray source and the charged selenium plate, and dusting the surface of such exposed plate with a dry developer material whereby such material is deposited on the plate to form an image in conformity with the electric charge remaining thereon.
